ADJUSTMENT CONTROL UNIT FOR A CHAIR

Frank Doerner, Waterloo, Ontario, Canada, assignor to
Doerner Products Co. Limited, Waterloo, Ontario,
Canada, a corporation of Canada

Filed Aug. 11, 1967, Ser. No. 8,239

Term of patent 14 years

(Cl. D15—1)

FIG. 3

FIG. 4

FIG. 5

FIG. 1 is a front perspective view of an adjustment control unit for a chair constructed in accordance with this design;

FIG. 2 is a rear perspective view thereof;

FIG. 3 is a plan view of the underside thereof;

FIG. 4 is a side elevation thereof;

FIG. 5 is a rear elevation thereof.

I claim:

The ornamental design for an adjustment control unit for a chair, as shown.
